UNITED STATES PATENT OFFICE

2,183,412

TIME DELAY RELAY

Marvin B. Sledd, Schenectady, N. Y., assignor to
 General Electric Company, a corporation of
 New York

Application December 16, 1938, Serial No. 246,181

5 Claims. (Cl. 175—320)

My invention relates to time delay relays of the type wherein the delay is determined by the time required for a capacitor to lose a certain amount of charge. Such a relay has been described and 5 claimed in the copending application of Elbert D. Schneider, Serial No. 155,518, filed July 24, 1937, assigned to the same assignee as the present application. With that relay it was found that under certain conditions, such as when it was 10 used to control loads that produced considerable drop in the voltage of the line supplying the relay there was a tendency for the load controlling contacts of the relay to chatter at the end of the timing period. It is an object of my invention to 15 provide an improved form of the relay disclosed in the aforesaid Schneider application which will avoid any tendency toward chattering.

My invention will be better understood from the following description taken in connection 20 with the accompanying drawing, and its scope will be pointed out in the appended claims.

In the single figure of the drawing which is a circuit diagram showing a somewhat simplified form of the relay disclosed in the aforesaid 25 Schneider application together with an embodiment of my invention, 1 and 2 represent the leads of a source of alternating current supply which, for example, may be a 60 cycle lighting circuit at 220 volts. Connected across the source 30 is the voltage divider 3 which is shown as comprising the resistor 4 and the potentiometer 5. The electron discharge device 7 having the anode 8, the control grid 9 and the cathode 10 is arranged to be energized from the source 1, 2, the 35 cathode being shown connected directly with the lead 2 through the single pole, single throw switch 11 and the anode being shown connected through the winding of the relay 12 with the other lead 1 of the source. The grid 9 connects with the movable contact 6 of the potentiometer through the 40 capacitor 20 which is shunted by the resistor 21 forming a leakage path through which the capacitor may lose its charge at a predetermined rate. The cathode 10, in addition to its connection with the lead 2 through the switch 11, has a permanent 45 connection with the lead 1 through the resistor 22. The apparatus thus far described is essentially that disclosed and claimed in the aforesaid Schneider application.

50 In the drawing of the present application, I have shown the relay 12 provided with a movable contact 23 arranged when the relay is energized to close the load circuit 24 including any suitable load device represented at 25. This load 55 circuit connects with the leads 1 and 2 whereby

the closing of the load circuit by the relay 12 may tend to produce a drop in voltage between those leads. The relay 12 is provided with another movable contact 26 and the cooperating fixed contacts 27, which latter connect through the 5 leads 28 with the capacitor 20 and the point 29 connecting with the grid and with one side of the leak resistor 21. The movable contact 26 is so arranged that when the relay 12 is operated the circuit controlled thereby between the capacitor 10 and the point 29 is opened.

Assuming the switch 11 to be in its open circuit position as illustrated, in which case no current flows in the anode-cathode circuit of the discharge device 7 and the relay 12 is deenergized, there will be a grid current flow during these half cycles, which for convenience will be termed the negative half cycles, at which the lead 1 is negative with respect to the lead 2. This grid current is that due to the potential difference 20 between the potentiometer contact 6 and the lead 1 and charges the capacitor 20 in such a manner that the side thereof which connects with the grid is negative, it being noted that the only connection of the cathode with the source at 25 this time is that through the resistor 22 to the lead 1. Thus, while the switch 11 is open, the negative half cycles of the supply voltage keep* the capacitor 20 in a charged condition.

When the switch 11 is closed the anode-cathode 30 circuit of the device 7 is closed whereby the device may function to pass current during the positive half cycles to operate the relay 12 under the control of the grid 9. Closing of the switch 11 also serves effectively to transfer the connection of the cathode from the lead 1 to the lead 2, it being noted that the connection of the cathode with the lead 2 is of negligible resistance. The charge formerly given to the capacitor 20 maintains the grid 9 sufficiently negative to prevent 40 current flow through the device 7 until the charges on the plates of the capacitor have had time to equalize through the resistor 21, or at least to become reduced to such a value that the device 7 will pass current sufficient to cause an 45 operation of the relay 12. After the operation of the relay 12, the switch 11 may be opened at which time the relay will move to open circuit position and the capacitor 20 will again become charged by the grid current of the device 7 during 50 the negative half cycles. It will thus be seen that after the closing of the switch 11 the relay 12 will be operated only after the lapse of a predetermined time interval. The duration of this 55 interval depends upon various factors such as the

capacitance of the capacitor, the resistance of the resistor in shunt therewith and the setting of the potentiometer. Adjustment of the latter provides a convenient method of varying the time delay interval as desired.

5 In the above described operation of the apparatus I have not taken into consideration the effect of the operation of the relay 12 upon the grid circuit of the device 7 nor the effect on the 10 line voltage of closing the load circuit 24. It has been found that in some cases the closing of the 15 load circuit at the end of the timing interval has caused the relay 12 to chatter. This is probably due to the fact that the closing of the load circuit produced a drop in the voltage supplied to the discharge device 7 so that the relay 12 became deenergized sufficiently to reopen the load circuit. The load thus being removed from the 20 supply leads the voltage supplied to the discharge device was immediately restored whence the device again passed sufficient current to re-operate the relay to reclose the load circuit. The above sequence of operation may continue to repeat itself until such time that the negative bias supplied to the grid by the capacitor 20 is insufficient to prevent the operation of the relay.

The additional contacts 26 and 27 of the relay 12 being arranged to open the connection between the capacitor and the grid when the relay 30 operates serves to reduce or to remove the biasing effect of the capacitor on the grid of the discharge device for it will be seen that upon the first operation of the relay 12 the connection between the capacitor and the grid is opened thus 35 removing whatever negative bias is being supplied by the capacitor to the grid. This removal of the negative bias supplied to the grid causes an increase in the current through the relay 12, and this increase prevents the relay 12 from becoming sufficiently deenergized by the drop in voltage to reopen the load circuit. Chattering is thus avoided.

What I claim as new and desire to secure by Letters Patent of the United States, is:

45 1. A time delay relay comprising a voltage divider arranged to be connected across a source of alternating current supply, a grid controlled electron discharge device having its anode and cathode connected with spaced points of said divider, a current responsive device in one of said 50 connections, a capacitor connected between said grid and a point of said divider between said spaced points, a switch in said cathode connection, a resistor connected between said cathode 55 and said divider at a point of the divider on the opposite side of said capacitor connection from said first mentioned cathode connection and means responsive to the operation of said current responsive device for reducing the effect of said capacitor on said grid.

60 2. A time delay relay comprising a source of supply of alternating current, a grid controlled electron discharge device having its anode and

cathode connected to be energized from said source, a current responsive device in one of said connections, a switch in said cathode connection, means connected with said cathode and grid and operable when said switch is open for producing a grid current during the negative half cycles of the alternating current, a capacitor in series with said grid arranged to be charged by said grid current and means controlled by said current responsive device for rendering the charge on 10 said capacitor ineffective to bias said grids.

3. A time delay relay comprising a voltage divider arranged to be connected across a source of alternating current supply, a grid controlled electron discharge device having its anode and 15 cathode connected with spaced points of said divider, a relay in one of said connections, a capacitor provided with a high resistance shunt connected between said grid and a point of said divider between said spaced points, a switch in 20 said cathode connection and a resistor connected between said cathode and said divider at a point thereof on the opposite side of said capacitor connection from said first mentioned cathode connection, said relay having cooperating contacts arranged to remove the effect of said capacitor on said grid.

4. A time delay relay comprising a source of supply of alternating current, a grid controlled electron discharge device having its anode and 30 cathode connected to be energized from said source, a relay in one of said connections, a switch in said cathode connection, means connected with said cathode and grid and operable when said switch is open for producing a grid current during the negative half cycles of the alternating current, and a capacitor having a high resistance shunt in series with said grid arranged to be charged by said grid current, said relay having 35 cooperating contacts operative to open the connection between the capacitor and the grid.

40 5. A time delay relay comprising a voltage divider arranged to be connected across a source of alternating current supply, a grid controlled electron discharge device having its anode and 45 cathode connected with spaced points of said divider, a current responsive device in one of said connections, a capacitor connected between said grid and a point of said divider between said spaced points, a switch in said cathode connection, a resistor connected between said cathode and said divider at a point thereof on the opposite side of said capacitor connection from said first mentioned cathode connection, a relay provided with a plurality of movable contacts connected in the anode circuit, a load circuit connected to be supplied from said source and to be controlled by one of said movable contacts and means whereby another of said movable contacts controls the connection between said capacitor and said grid.
